REFLECTOR AND FIXTURE

Harold S. Johnston, New Kensington, Pa.

Application August 4, 1939, Serial No. 288,467

1 Claim. (Cl. 240—78)

The present invention relates to new and improved fixtures and reflectors primarily adapted for use with fluorescent tube lamps.

An important object of the invention resides in the provision of a fixture and reflector that affords improved illumination obtaining full value of light from the fluorescent tube or lamp.

A further object of the invention is to provide a fixture and reflector that can be assembled in various shapes for use in illuminating rooms of dwellings, windows, display cases and the like.

A still further object of the invention resides in the provision of a fixture and reflector for fluorescent tube lamps that may be used as a single unit or in multiple units and adapted to be used with or without a glass panel in front of the reflector and lamp.

The invention will be fully and comprehensively understood from a consideration of the following detailed description when read in connection with the accompanying drawings which form a part of the application.

In the drawings:

Figure 1 is a side elevational view of a reflector and fixture embodying the features of the present invention.

Figure 2 is a vertical sectional view taken substantially on line 2—2 of Figure 1.

Figure 3 is a perspective view of the reflector element removed from the fixture.

Figure 4 is a vertical sectional view of a reflector and fixture and illustrating the use of a curved glass enclosure.

Figure 5 is a vertical sectional view of a reflector and fixture of a single unit.

Figure 6 is a vertical sectional view of a reflector and fixture illustrating a double unit.

Figure 7 is a vertical sectional view illustrating the reflector in use in the corner of a display case or the like.

Referring to the drawings for a more detailed description thereof, a fixture comprising a substantially rectangular-shaped frame is indicated generally by the reference numeral 10, the same being formed of any desired light weight material and adapted to be attached to a ceiling or the like by any desired means. As shown in Figure 2 of the drawings, the fixture 10 is substantially hollow being formed with angular-shaped side and end portions 11 and 12, respectively. The bottom 13 of the fixture has a relatively flat surface with the opposed sides thereof having an offset portion 14 to which is attached the reflector generally designated by the numeral 15.

The reflector 15 is preferably formed of highly polished aluminum or similar material, the side portions 16 of which are shaped to fit within the offset portion 14 of the fixture 10 for attaching the reflector thereto by means of bolts or the like 17. The reflector 15 is convexed longitudinally as indicated at 18 to form a multiplicity of individual corrugations which cooperate with the fluorescent tube lamps 19 to reflect the beams of light into every section of the room, display case or the like with which the fixture is used.

The tubes 19 extend longitudinally of the fixture and are disposed in front of the apex of each corrugation as more clearly shown in Figure 2 of the drawings, said tubes being supported in brackets 20 depending from the fixture 10. An important feature of the invention resides in assembling the fixture whereby the inverted V-shaped portions of the reflector rise to a point directly above the fluorescent tube whereby full benefit of light from the tube is obtained.

If desired, a relatively flat sheet of transparent glass 21 may be supported in front of the tubes and reflectors, the same being supported from the fixture by means of adjustable brackets 22. As is to be understood, the brackets 22 can be lengthened or shortened, through their intermediate portions 23 for bringing the glass panel 21 closer to or further away from the tubes 19.

In Figure 4 of the drawings, there is illustrated a fixture and reflector identical with that disclosed in Figures 1, 2 and 3. It will be noted, however, that there is employed a curved transparent glass dome 24 in place of the flat glass panel 21 whereby the reflector 15 and tubes 19 are completely enclosed. The curved dome 24 is associated with the fixture 10 and held thereto by means of a retaining ring 25, said ring being removably attached to the fixture by a threaded screw or the like 26 which construction permits removal and replacement of the dome 24.

In Figure 5 of the drawings, there is illustrated a single unit embodying a miniature fixture 27 having attached thereto a reflector 28 which reflector includes a single corrugation 29 beneath which is positioned a fluorescent tube 30. The reflector 28 and tube 30 are attached to the fixture 27, in the manner previously described. In Figure 6 of the drawings, there is illustrated a double unit the use of a glass panel or dome, as in the previously described forms, has been dispensed with.

A further modified form of the invention is disclosed in Figure 7 of the drawings, which modification represents a double unit in that a

pair of tubes 31 extend from the fixture 32 being placed at the apex of each of the corrugations 33. In this form of the invention, it will be noted that the reflector 34 is formed with a slight curvature to provide the longitudinal corrugations 33, the curvature assisting in providing improved illumination when using this type of unit.

In Figure 7 of the drawings, a reflector of the type hereinabove described is disclosed in use within the corner of a display case 35 and it will be noted that the fluorescent tube 36 is positioned directly in front of the corrugation 37 with the side portions 38 of the reflector disposed against the walls of the display case. A glass shield 39 is supported in front of the tube 36, the same being retained by means of a ring or the like 40. When so used light from the tube 36 will be completely reflected to all parts of the display case.

Also it will be understood, of course, by those skilled in the art that variations in the hereinabove described device involving the substitution of substantial equivalents for the devices de-

scribed are intended to be comprehended within the spirit of the present invention and that the invention is capable of extended application and is not confined to the exact showing of the drawings nor to the precise construction described and, therefore, such changes and modifications may be made therein as do not affect the spirit of the invention nor exceed the scope thereof as expressed in the appended claim.

10. What is claimed is:

A fixture for fluorescent tubes, comprising a substantially rectangular shaped frame with its outer face having rectangular shaped recesses extending across the same adjacent the side edges, 15 a reflector having convex corrugations engaging the frame and provided with flat faces beyond the corrugations engaging the frame, the side edges of the flat faces having rectangular inwardly extending side edges entering said rectangular recesses, and bolts passing through the said rectangular side edges and the bottom of said rectangular recesses.

HAROLD S. JOHNSTON.
